FOOT LEVELER

Clarence H. Stemmons, Kansas City, Mo.

Application April 30, 1945, Serial No. 591,203

2 Claims. (Cl. 36—71)

1

This invention relates to foot comforting appliances of the type insertable into a shoe for the purpose of supporting the arches of the wearer, absorbing the shocks and jars to which the outer and inner longitudinal arches, the heel bone and the fifth metatarsal head are subjected because of their peculiar weight-bearing function.

The primary aim of the invention is to provide an appliance of the aforementioned character and having the ability of comforting the wearer because of the shocks experienced incident to walking, and also capable of preventing the elongation of the foot or the slipping forward of the foot in the shoe and capable of correcting pronation or supination.

An even further aim of this invention is to provide an insertable appliance for shoes, having the ability of elevating the longitudinal arches of the wearer as a shock absorbing result is obtained.

Other objects of this invention are to provide a foot leveler capable of relieving shoe pressure and protecting the foot from projecting laterally and thereby extend the shoe to an undesirable degree; capable of adjustment with respect to supporting the longitudinal arches; and having means for supplementing the metatarsal arch supporting pillow of the appliance, whereby the individual user may adjust the appliance to suit particular conditions and to accommodate shoes of various makes.

Still further aims of this invention will appear during the course of the following specification, referring to the accompanying drawing, wherein:

Fig. 1 is a top plan view of a foot leveler made in accordance with the present invention.

Fig. 2 is an edge elevational view thereof.

Fig. 3 is an inverted plan view with parts broken away and separated for clearness of disclosure.

Fig. 4 is a cross sectional view taken on line IV—IV of Fig. 1.

Fig. 5 is a similar sectional view taken on line V—V of Fig. 1; and

Fig. 6 is a sectional view taken on line VI—VI of Fig. 1.

The steps in the method of producing a foot lever or appliance of the character illustrated and constituting the subject matter of this invention, are of importance and will appear in detail after a description of that form of the invention which has been chosen for illustration.

The appliance shown in the drawing is one particularly formed for introduction into the left shoe of the wearer where the arch wing 10 will underlie the outer edge of the inner longitudinal arch of the foot. This wing 10 is a lateral ex-

1 tension formed on the two superimposed sheets of flexible material 12 and 14 respectively, the former being the uppermost portion of the appliance when it is in the operative position.

5 Pads of soft resilient material are interposed between sheets 12 and 14 during the first step in the method of producing the appliance. These pads are disposed along the outer portion of the appliance and therefore, below the outer zones of 10 the bottom of the foot, to establish cushions, one of which is at the heel, while another is below the cuboid and formed to cushion that member of the foot.

Pad or cushion 16 is thicker along the edge 15 thereof near the outer edges of material 12 and 14. This pad progressively decreases in thickness as its inner edge is approached and also tapers to a feather edge as it nears pad 18. This latter pad is thicker at its outer edge and its top 20 surface is arched as clearly shown in Fig. 2. In other words, pad 18 arches upwardly or inwardly and presents a convex surface above which the cuboid of the foot is disposed.

A third pad 20 formed of resilient cushioning

25 material in the nature of soft sponge rubber, lies between sheets of material 12 and 14, and, like pads 16 and 18 is held in place by lines of stitching. Stitches 22 pass through material 12 and 14 and follow the periphery of pad 20. Stitches

30 24 are placed around the inner arcuate edge of pad 18 and this line of stitching 24 is carried diagonally across the appliance along the inner straight edge of pad 16 and thence toward the forward end of the appliance where it extends 35 transversely thereacross and continues into a short line of stitching terminating near pad 18. It is this stitching 22 and 24 that is created after the pads have been cemented in place between sheets of material 12 and 14. In actual produc-

40 tion the pads are cemented between sheets 12 and 14 and then the sheets and pads are embossed in a press to snugly fit sheets 12 and 14 in a directly superimposed relation over the areas thereof not occupied by the three pads 16, 18 and 20.

45 The pressure is so applied around pad 20 as to cause a lateral projection thereof to each side of the superimposed sheets of material 12 and 14. In other words, there is an upwardly and downwardly disposed embossment where pad 20 is positioned. This pad 20 is L-shaped and cooperates with pad 18 in creating an effective metatarsal pillow, the rearwardly extended stem whereof supports the fourth metatarsal bone and part of the fifth metatarsal bone.

50 55 After the two sheets of material 12 and 14 are

assembled with pads 16, 18 and 20 as above set forth, an additional sheet of leather, imitation leather, or flexible substance of desirable character, is cemented to the lowermost sheet of material 14. A transverse line of stitching 27 positively anchors all sheets of material, i. e. 12, 14 and 26 together if the cementing is thought to be inadequate. This last mentioned sheet 26 is formed as illustrated in Fig. 3, and is provided with a pair of longitudinal slits 28 at its forward end for the reception of a supplementary L-shaped pad 30, if the wearer needs additional metatarsal support or cushioning. This pad 30 is formed of soft, sponge rubber, and is easily slipped to place through slits 28, as clearly shown in Fig. 3. The form of this pad 30 is agreeable to the contour of pad 20 and will underlie the same for a supplemental action when in the position shown in Fig. 3.

Sheet material 26 carries a pad 32 and the adhesive 34 is so applied as to leave a pocket 36 having the mouth thereof at the edge of the appliance beneath wing 10. This pad 32 supports both the inner and outer longitudinal arches and if insufficient in thickness, may be supplemented by the introduction into pocket 36 of a pad 38, the character whereof is illustrated in Fig. 5. Pad 32 extends transversely and completely across the appliance and beneath pad 18 to add further resiliency and height thereto.

Pad 38 cannot be projected into pocket 36 a distance beyond that allowed by a line established by cement 34 and, manifestly, no increase in the thickness of the appliance where pads 18 and 32 overlie each other, will occur.

From the above it will be apparent that pad 16 elevates the heel and that its thickest and most resiliant portion underlies the lowermost part of the os calcis or heel bone. An effective shock absorbing action is the result. Pad 18 underlies the cuboid and the contour of this pad is such as to complement the foot beneath the cuboid to afford the greatest amount of support with a minimum amount of shock. In fact, this pad 18 allows normal action of the bones of the foot adjacent the cuboid as a gentle supporting action occurs.

The form of pad 20 and the advantages arising from the special contour, have been clarified above, as has been the benefits emanating from the particular manner in which the outer sheet of material 26 is applied. The two superimposed sheets of material 12 and 14 are positively held against relative displacement due to any sliding action while material 26 is so affixed as to present a pocket for the reception of the pad 38 and member 30.

The pillow-like form of pad 18 and the inclined upper face of material 12, due to the form of pad 16, assures that the foot of the wearer will not move forwardly into the shoe to crowd the toes.

Ventilating openings 40, 42 and 44 insure proper distribution of the air within the shoe beneath the foot of the wearer.

When pad 30 is inserted, the material between slits 28 is easily lifted because there is no cement over that part of the sheet 26 having slits 28 therein. Obviously, pad 30 is selectively used and when not inserted as shown in Fig. 3, the bottom of the appliance is smooth to lie directly upon the conventional sock liner of the shoe.

Benefits arising from appliances made as shown and described, fulfill the objects of the invention,

but since the principles contemplated might be embodied in appliances having physical characteristics different from those shown and specified, it is desired to be limited only by the spirit of the invention and scope of the appended claims.

Having thus described the invention, what is claimed as new and desired to be secured by Letters Patent is:

1. An appliance of the character described comprising a number of pieces of superimposed sheet material formed to fit in a shoe beneath the foot of the wearer; and a heel pad, a cuboid pad and a metatarsal pillow, all formed from flexible material and all disposed between certain of the said pieces of sheet material, said heel pad being relatively thick at its outer edges and terminating at a thin edge extending diagonally across the appliance, said cuboid pad having a convex upper surface and extending from the heel pad adjacent one end of said thin edge thereof, said pillow being L-shaped and having one leg thereof beneath the second, third and fourth metatarsal heads, and the other leg thereof beneath the fourth metatarsal bone of the foot of the wearer, the free end of said other leg of the pillow extending from the cuboid pad in opposed relation to said heel pad.

2. An appliance of the character described comprising a number of pieces of superimposed sheet material formed to fit in a shoe beneath the foot of the wearer; a heel pad, a cuboid pad and a metatarsal pillow, all formed from flexible material and all disposed between certain of the said pieces of sheet material, said heel pad being relatively thick at its outer edges and terminating at a thin edge extending diagonally across the appliance, said cuboid pad having a convex upper surface and extending from the heel pad adjacent one end of said thin edge thereof, said pillow being L-shaped and having one leg thereof beneath the second, third and fourth metatarsal heads, and the other leg thereof beneath the fourth metatarsal bone of the foot of the wearer, the free end of said other leg of the pillow extending from the cuboid pad in opposed relation to said heel pad.

3. An appliance of the character described comprising a number of pieces of superimposed sheet material formed to fit in a shoe beneath the foot of the wearer; a heel pad, a cuboid pad and a metatarsal pillow, all formed from flexible material and all disposed between certain of the said pieces of sheet material, said heel pad being relatively thick at its outer edges and terminating at a thin edge extending diagonally across the appliance, said cuboid pad having a convex upper surface and extending from the heel pad adjacent one end of said thin edge thereof, said pillow being L-shaped and having one leg thereof beneath the second, third and fourth metatarsal heads, and the other leg thereof beneath the fourth metatarsal bone of the foot of the wearer, the free end of said other leg of the pillow extending from the cuboid pad in opposed relation to said heel pad.

4. An appliance of the character described comprising a number of pieces of superimposed sheet material formed to fit in a shoe beneath the foot of the wearer; a heel pad, a cuboid pad and a metatarsal pillow, all formed from flexible material and all disposed between certain of the said pieces of sheet material, said heel pad being relatively thick at its outer edges and terminating at a thin edge extending diagonally across the appliance, said cuboid pad having a convex upper surface and extending from the heel pad adjacent one end of said thin edge thereof, said pillow being L-shaped and having one leg thereof beneath the second, third and fourth metatarsal heads, and the other leg thereof beneath the fourth metatarsal bone of the foot of the wearer, the free end of said other leg of the pillow extending from the cuboid pad in opposed relation to said heel pad; and lines of stitching passing through certain of said sheets and around each of the pads and the pillow respectively to hold the pads in place and in separate independent relationship, said pads and the pillow having their respective uppermost contours pressed into the normally uppermost sheet of material to create embossments having contours equivalent to the underlying pads and pillow.
